UNITED STATES PATENT OFFICE.

JOHN T. CASEY, OF PHILADELPHIA, PENNSYLVANIA, ASSIGNOR TO KEY-STONE LANTERN COMPANY, A CORPORATION OF NEW JERSEY.

LANTERN.

SPECIFICATION forming part of Letters Patent No. 729,844, dated June 2, 1903.

Application filed December 3, 1902. Serial No. 133,720. (No model.)

To all whom it may concern:

Be it known that I, JOHN T. CASEY, a citizen of the United States, residing at Philadelphia, in the county of Philadelphia and State of Pennsylvania, have invented certain new and useful Improvements in Lanterns, of which the following is a specification, reference being had to the accompanying drawings, forming part thereof.

10 This improvement relates to lanterns primarily of the type known to the trade as "railroad-lanterns," the principal object of my invention being to construct the bottom or base so that the incoming air necessary to support 15 combustion shall be induced to follow a circuitous course before entering the lantern, the effect of such action being to break or modify the force of the draft or of wind entering the air-supply openings before reaching 20 the burner.

A further object is to provide means for securely holding the rotatable oil-reservoir in position after it has been turned to adjust the wick.

25 Other objects of my invention are herein-after pointed out.

Referring to the drawings, Figure 1 represents a vertical central section of a lantern having my improvements applied thereto; 30 Fig. 2, a horizontal section on the line 2-2 of Fig. 1, and Fig. 3 a corresponding view of a modification.

Similar letters and numerals of reference indicate similar parts in the several figures.

35 Attached to the center of a lantern-base A is an upright cylindrical casing B, within which an oil-reservoir C, carrying a burner D, is adapted to rotate. Fixed to the base A and surrounding the casing B when assembled is a collar E, which fits over the lower end of the cylindrical bottom portion F of the lantern and by means of fastening devices on said ring connects the base A to the lantern-body.

40 The cylindrical bottom portion F, or "cylinder," as it will be hereinafter called, is of greater diameter at the bottom, where it enters the collar E, than at its upper end, which supports the globe G, a shoulder f being 45 formed at the junction of the two diameters. Seated on the shoulder f is a flat guard-

supporting ring H, having an upturned flange h on its inner edge. On the cylinder F, above the flange h, is formed a bead f', which, in connection with the shoulder f, holds the ring H in position upon the cylinder. The globe-guards I are attached at their lower ends to the ring H. Openings f² for the admission of air are made in the cylinder F below the shoulder f.

55 A cylindrical wind-shield K, with flaring upper and lower ends k k', is placed within the cylinder F, between it and the casing B. The lower flared end k of the wind-shield K, provided with a series of openings k², through 60 which air passes to the burner, rests upon the beaded lower end of the cylinder F and is soldered or otherwise attached thereto, while the upper flare k' extends into a groove formed by beading the cylinder, as at f'. 70 Under the construction provided an annular air-space or quieting-chamber 2 is formed between the cylinder F and the wind-shield K, a second annular space or air-passage 3 extending between the wind-shield K and the 75 casing B. Air to support combustion passes through the openings f² in the cylinder F and into the quieting-chamber 2, thence turning downwardly through the perforations k² in the lower end of the wind-shield K, and 80 finally passing up through the annular space 3 to the burner. In traveling this circuitous course the force of the incoming air is broken and a direct draft prevented from reaching the burner, the result being the production 85 of a steady and not readily extinguishable flame.

The casing B, within which the oil-cup rotates, is secured to the base A by reason of a slight reduction of its diameter (effected by 90 drawing) at its bottom, enabling it to pass through a central opening in the base. The reduced portion of the casing is then spun or bent around the edge of the opening and over a ring b', of stiff metal, soldered to the base A, 95 thus forming a comparatively broad and smooth bearing b for the oil-reservoir C. A cap-piece L, soldered to the upper end of the casing B, is furnished with a central aperture d for the passage through it of the burner 100 D. A circular rack d' on the cap L surrounds the aperture d and engages with and turns a

pinion d^3 on the wick-feeding shaft, by means of which arrangement the wick is raised or lowered as the oil-reservoir C is rotated in one or the other direction.

5. The oil-reservoir is contained partly within the casing B and partly below it in the base A, the latter being of lesser diameter and made to be grasped by the hand when the reservoir is to be turned. A shoulder c on the oil-cup at the point where it emerges from the casing B is supported by the bearing b , formed, as described, by the lower end of the casing B.

To prevent the oil-reservoir from turning too easily, and thus changing the power or character of the light, a spring M, (see Figs. 2 and 3,) riveted to the outside of the casing B, extends through a hole b^3 in said casing and bears with greater or lesser friction upon the outer surface of the oil-reservoir C, thus effectually holding it against accidental rotation. A modified form of spring is shown in Fig. 3.

Throughout this specification I have described the casing B as fixed and the oil-reservoir as movable; but the casing may be made movable and the reservoir fixed.

I do not restrict myself to the exact details of construction, combination, and arrangement herein set forth, it being obvious that minor variations thereof not involving the exercise of invention may be made by the skilled mechanic, and such departures from what is herein described and claimed not involving invention I consider as within the scope and terms of my claims.

Having thus described my invention, I claim—

1. In a lantern, the combination with a cylinder or cylindrical bottom portion having air-inlets, of a base removably attached thereto, a casing inclosing an oil-reservoir and attached to the base, and an annular wind-shield between the cylinder and the casing and provided with air-openings, the construction being such that a quieting-chamber is formed between the cylinder and the wind-shield and a passage also formed between the wind-shield and the casing through which air

may reach the burner, substantially as set forth.

2. In a lantern, the combination with a cylinder or cylindrical bottom portion provided with an internal groove near its upper end and a series of openings below said groove, of a wind-shield flared at its upper and lower ends, the upper flare entering said groove and the lower flare, attached to the bottom of the cylinder, being provided with perforations, a quieting-chamber being formed between the cylinder and the wind-shield, substantially as set forth.

3. In a lantern, the combination with a cylinder or cylindrical bottom portion provided with an internal groove near its upper end and a series of openings below said groove, of a wind-shield flared at its upper and lower ends, the upper flare entering said groove and the lower flare, attached to the bottom of the cylinder, being provided with perforations, a casing for an oil-reservoir, a quieting-chamber being thus formed between the cylinder and the wind-shield and an annular air-passage being formed between said wind-shield and casing, substantially as set forth.

4. In a lantern having a base, the combination of a casing secured thereto, a rotatable oil-reservoir contained within said casing, means attached to one of said elements to bear with yielding frictional contact upon the other element, and means for rotating said reservoir in order to adjust the wick, substantially as set forth.

5. In a lantern having a base, the combination of a casing secured thereto, an oil-reservoir adapted to rotate within said casing, means for rotating said reservoir in order to adjust the wick, and a spring secured to the casing arranged to bear with frictional contact upon the surface of the oil-reservoir, substantially as set forth.

In testimony whereof I hereunto set my hand and seal.

JOHN T. CASEY. [L. S.]
